D. I. CLARKE.
WIRE STRETCHER.
APPLICATION FILED DEC. 1, 1916.

1,331,321.

Patented Feb. 17, 1920.

UNITED STATES PATENT OFFICE.

DELBERT I. CLARKE, OF ELAINE, ARKANSAS.

WIRE-STRETCHER.

1,331,321.

Specification of Letters Patent.

Patented Feb. 17, 1920.

Application filed December 1, 1916. Serial No. 134,488.

To all whom it may concern:

Be it known that I, DELBERT I. CLARKE, a citizen of the United States, residing at Elaine, in the county of Phillips and State 5 of Arkansas, have invented certain new and useful Improvements in Wire-Stretchers, of which the following is a specification.

The present invention relates to the class of pushing and pulling and has particular 10 reference to new and useful improvements in wire fence stretchers.

An object of my invention is to provide in a novel and cheaply constructed device an improved type of wire fence puller or 15 stretcher which may be quickly and easily applied for use in stretching a fence or the like, and is strong and durable and effective in operation.

Another object of my invention is to provide 20 a wire fence stretcher of the class described having a novel and improved form of wire fence engaging structure as well as a novel means for exerting force upon the fence engaging elements to stretch the fence.

25 A further object of my invention is to provide means for engagement with a wire clamp whereby as a greater pulling force is exerted upon the clamp the same will be caused to more firmly engage the fence wire 30 thereby obviating any danger of slipping of the wire fence while being stretched.

A still further object of my invention is to provide an article of the class described which may be cheaply manufactured and 35 placed upon the market at a reasonable cost, and may be as readily adapted for stretching a single wire as for stretching a plurality of the same.

40 Other objects and advantages of my improved wire stretcher will appear from the following detail description and the claim, taken with an inspection of the accompanying drawing, in which:

Figure 1 is a side elevational view of a 45 wire stretcher embodying the improvements of my invention, the same being shown applied in operative position;

Fig. 2 is an enlarged perspective view of the clamp and holding members;

50 Fig. 3 is an enlarged fragmental longitudinal sectional view of the clamp showing the retaining member; and

Fig. 4 is an enlarged elevational view of the clamp gripping element.

Referring more particularly to the drawing, wherein similar characters of reference designate like and corresponding parts throughout the various views, P designates the fence post and F designates in its entirety a wire fence structure. The wire fence 55 structure is composed of any standard arrangement of vertical and longitudinal intersecting strands of wire 1 and 2, respectively, said strands being engaged by the clamps in a manner which will hereinafter 60 appear.

The clamps or wire engaging device is 65 designated C in its entirety and is composed of two detachable sections 10 and 11, the sections 10 forming the clamp base and carrying a plurality of wire fence engaging pins 70 12, best shown in Fig. 3. The section 11 is provided with recesses to accommodate the pins 12 when in clamping position.

The sections 10 and 11 are detachably and 75 hingedly connected at adjacent ends, said connection being afforded by means of an angle-iron 14 bolted or otherwise fastened to the outer face of the section 10 and projecting laterally of the section in the direction of the section 11. A plate 15 is carried by the section 11 and bolted or otherwise permanently secured thereto, said plate being provided with reduced portions 16 forming an head 17 adapted for insertion through 80 an opening provided in the angle-iron 14. The opening in said angle-iron is of a width to accommodate the narrow portion of the plate 15 when in the position shown in Figs. 1 and 2 and of a length to accommodate the 85 head 17 so that said sections 10 and 11 may be disconnected.

A temporary holding device for the sections when applying the same to the fence wire is provided, said holding device embodying a hinge plate 18, mounted preferably on the outer surface of the section 10 at the end opposite the angle-iron 14, a wire loop 19 being hingedly mounted in said plate 18 and adapted to embrace both of the 90 sections 10 and 11 when in clamping position. A lever 20 is pivoted as at 21 on the wire loop 19, said lever having a cam portion 22 to engage a wearing plate 23 mount-

ed on the outer surface of the section 11. The plate 23 is provided with a shoulder 24 to prevent accidental displacement of the cam when in temporary use. In order to effectively maintain the sections 10 and 11 in clamping engagement with the fence F I provide a bolt 25 demountably secured in complementary openings 26 formed in said sections 10 and 11, the threaded end of said bolt having a knurled nut 27 thereon, said nut being adapted to clampingly engage said section 11, the head of the bolt engaging the other section. After a temporary engagement of the clamp C with the wire fence 15 has been effected by the cam 22 the nut 27 is brought into position for maintaining the clamp in engagement with the fence during the stretching operation.

I provide means for exerting force upon 20 the clamp in the direction in which the fence is to be stretched, said means including a tubular member 28 provided with two loops 29 on the outer surface adjacent opposite ends and a single loop 30 at a point intermediate the length of the tube and approximately diametrically opposite said loops. A chain 31 extends from the loop 30, the free end of the chain 31 having a ring 32 carried thereby. A pair of hook members 33 extend from the ring 32, said hook members engaging rings 34 carried by the free ends of chains 35, said chains being arranged in pairs and connecting the clamp engaging members *c* and *c'* with the rings 34.

As both of the members *c* and *c'* are identical in construction I shall describe but one of the same. Referring to Fig. 4 wherein one of the members, namely the member *c* is shown I provide a pair of straps, one of 40 the straps having an opening 37 therein and the other strap having an enlarged head 38 to engage through said opening and connect the free ends of said straps. A pair of the chains 35 are shown, the free ends of the 45 chains being connected at 39 to opposite points on the strap members, the intermediate portions of the chains extending through openings 40 formed in said strap members. Thus it will be seen that when force is exerted upon both of the strap members simultaneously, said strap members will be brought into clamping engagement with an object inserted therebetween. In the present instance the strap members are to be engaged about the sections 10 and 11 of the 50 clamp C, grooves 41 being provided in the opposite faces of said members 10 and 11 to receive said straps.

Chains 42 and 43 extend from the loops 60 29 carried by the tube 28, said chains having hook members 44 and 45 on their free ends. One of the hook members is engaged with a ring 46, said ring being carried by the free ends of a chain 47, temporarily connected 65 to the fence post C in any desired manner.

A lever 48 is provided, the same being insertible in the tube 28.

In use the stretcher of my invention is applied as shown in Fig. 1, the chain 47 being connected with the post P and the chain 70 42 connected with the ring 46. The chains 31 and 35 are connected to the members *c* and *c'* after the same having been disposed about the clamp C. The pins 12 carried in the section 10 serve to engage the vertical 75 strands of wire 1 and exert a pull upon the fence F when the tubular member is rocked to perform this function.

By oscillating the lever 48 the pull will be directed upon the chains 35 tightening 80 the fence to a certain degree. Upon a movement toward the post P of the lever 48 the hook 45 is engaged with one of the links of the chain 47. The lever is now oscillated 85 in the opposite direction and the hook 44 disengaged from the ring 46 and engaged with one of the links of the chain 47. This operation is repeated progressively until the fence is tightened to the desired degree. In order to simplify the showing of the device the tubular member 28 has been shown 90 in a vertical position, but of course, it is to be understood that in actual use this tubular member will operate horizontally. Of course, I do not limit myself to the exact 95 use of the tubular member since any convenient position of operation may be employed. I desire to lay particular stress upon the extreme simplicity of my improved stretcher in view of the function accomplished thereby, and it will be readily apparent that the device may be cheaply constructed and placed on the market at a reasonable figure. All of the parts are constructed from stock material which can be 100 bought wholesale from any hardware manufacturer and requiring special dies only for the straps 36 and the plates 14 and 15.

From the above description taken in connection with the accompanying drawing, it 110 is thought that a clear and comprehensive understanding of the construction, operation and advantages of my invention may be had, and while I have shown and described the device as embodying a specific structure, 115 I desire that it be understood that such changes may be made in said structure as do not depart from the spirit and scope of the invention as claimed.

Having thus fully described my invention, 120 what I claim as new and desire to secure by Letters Patent, is:—

In a device of the character described, means for exerting force upon the clamping element of a wire stretcher, comprising 125 a tubular member of uniform diameter in cross section throughout its length for receiving a lever in either end thereof, a pair of loops provided on said member adjacent opposite ends at one side of the same, a 130

single loop provided on the other side of the member at a point intermediate the length of the same and diametrically opposite to said loops, a chain extending from

5 said single loop, a ring formed on the free end of the chain, a pair of hooks extending from said ring and adapted to engage with said clamping element, a chain connected

to each of said pair of loops, and hooks on the free ends of said chains whereby either 10 of the same may be connected with a fence post.

In testimony whereof I affix my signature hereto.

DELBERT I. CLARKE.
